UNITED STATES PATENT OFFICE

2,390,547

TORQUE AMPLIFIER

Howard M. McCoy, Fairfield, Ohio

Application July 8, 1944, Serial No. 544,129

2 Claims. (Cl. 172—239)

(Granted under the act of March 3, 1883, as amended April 30, 1928; 370 O. G. 757)

The invention described herein may be manufactured and used by or for the Government for governmental purposes, without the payment to me of any royalty thereon.

This invention relates to torque amplifiers, and among other objects, aims to provide an improved torque amplifier having proportionalizing (follow-up) means to minimize hunting. According to the preferred form of the invention, proportionalizing by rate as well as by time is made possible, to reduce hunting to the lowest practicable extent. However, the invention in its broadest aspect is independent of proportionalizing; it provides a simple, rugged, inexpensive remote positioning device for controlling whatever torque amplification is necessary from a tele-signal. As the angular position of the power take-off shaft is a direct function of the position of the master control, a position indicator associated with the master control may indicate the angles or positions of many things, for example, the angles of aircraft trim tabs. The invention could also be used to indicate the position of a gun turret, an antenna reel, a cowl flap, etc.

It is old, as in the Heath Patent No. 1,292,315, dated January 21, 1919, to synchronize two or more motors by means of apparatus comprising two or more threaded hubs or nuts, each of which travels back and forth on a shaft (in a direction determined by the motor which is running at the slower speed) to close switches which cut out resistances in the circuit of the slower motor, thereby to cause the latter to pick up speed until the speed of all the motors is the same. According to the Kessler Patent No. 2,023,139, dated December 3, 1935, a screw threaded shaft is adjusted by means of a crank to effect changes in the time intervals of reversing of electric current driving a motor operating a rotary furnace. Also limit switches of the traveling nut type for controlling electric motors are well known, as disclosed in Everett et al. No. 881,565, dated March 10, 1908, and Burrowes 838,681, dated December 18, 1906. Such prior art constructions, however, do not have the functions and advantages of my torque amplifier.

In the accompanying drawing forming a part of this specification, the single figure is a diagrammatic view of one form of apparatus embodying the invention.

Referring particularly to the drawing, a reversible electric servomotor 5 has a spring-loaded solenoid-released brake and clutch 6 simultaneously energized with the motor 5, to cause immediate stoppage of the motor 5 upon cutting off

power, which reaches the servomotor fields through the leads 7, 8, 9. Such brakes and clutches are conventional in electric servomotor art. They are used to minimize hunting. The 5 motorshaft 10 drives a pinion 11 which is illustrative of any power take-off that may be suitable to the use of the motor. Instead of a pinion, a torque arm, a pulley or some other driving element may be fixed to the motorshaft. In the 10 diagrammatic showing of the invention, motorshaft 10 is extended beyond the power take-off and its extension 10a is supported by anti-friction bearings 12, 13. An elongated spur gear 14 is rigidly fixed upon the shaft extension 10a and hence is driven in either direction by the servomotor when energized; however, in actual practice, reduction gearing (not shown) may be interposed between the shaft which drives the elongated gear 14 and the motorshaft. 15 To govern the servomotor, a master control is provided which in the illustrative embodiment is a crank wheel 15 secured to one end of a flexible shaft (not shown) inclosed within a flexible cable 16. The flexible shaft is secured at its other end 20 to the end of a shaft 17 rotatably supported by antifriction bearings 18, 19, and parallel to shaft extension 10a. Shaft 17 may have a lead screw secured thereto or, as shown, has screw threads 25 cut thereon for a portion of its length which is nearly as long as the elongated gear 14. A spur gear 21 is internally threaded to engage with threads 20, and is in mesh with the elongated spur gear 14, so that when the latter is driven by the servomotor, spur gear 21 will travel in one direction or the other axially of shaft 17. It is thus seen that the angular position of the object driven from power take-off 11 bears a constant relation (depending on gear reductions) to the angular position of control crank 15. Spur gear 21 cannot normally reach the end of the threaded portion 20, because the size and speed-power characteristics of servomotor 5 are selected for whatever object is driven from power take-off 11 to cause gear 21 to return to the neutral position 30 shown before gear 21 can run off the thread. However, when the elongated gear 14 is stationary, spur gear 21 will be locked against rotation, and any turning of shaft 17 by means of the operator-controlled crank wheel 15 will move 35 spur gear 21 longitudinally of shaft 17, to effect an adjustment which will now be described. 40 Embracing gear 21 is a bifurcated yoke 23 which is substantially in contact with either face of gear 21, or if preferred, antifriction bearings (not shown) will be interposed between the ends of 45 50 55

yoke 23 and the faces of gear 21. Fixed to and extending outwardly from yoke 21 is an arm 23a having an annular yoke 24 at its opposite end, yoke 24, in the neutral position of the parts, surrounding a stop collar 25 secured to or integral with a splined shaft 26. Shaft 26 is continuously driven by a constant speed motor 27 through reduction gear train 28, which is illustrative of any speed reduction drive. A speed governor 29 is provided to permit the operator to adjust the speed of motor 27. A pair of cam cylinders 30, 31 are splined on shaft 26 and each has a cam 32, 33 respectively formed thereon, these cams being mirror images of each other. A pair of "soft" coil springs 34, 35 surround shaft 26 and press against the ends of cam cylinders 30, 31 respectively to resist sliding of the cam cylinders in either direction from the illustrated neutral central position, wherein both cam cylinders abut the end faces of stop collar 25. Shaft 26 is supported in antifriction bearings 36, 37. By means of the construction so far described, the operator by turning crank wheel 15 may shift either cam cylinder along the continuously rotating shaft 26 against the resistance of the corresponding coil spring. Also, the servomotor may move either cam cylinder as determined by the direction of rotation of motor shaft 10.

Cams 32, 33 are designed to engage rollers 38, 39 carried on the ends of bell crank levers 40, 41 respectively, springs 42, 43 holding the rollers normally in contact with the peripheries of the cam cylinders. Obviously the bell crank levers are cam followers. However, when the cam cylinders are in the neutral position, which is illustrated, the rollers 38, 39 ride over the respective cam cylinders without contacting the cams, due to the fact that the cams terminate short of the ends of the cylinders. In the neutral position the cam followers are therefore not swung on their pivots 44, and no closing of the servomotor circuits can take place. But when one of the cam cylinders has been moved out of the neutral position, one of the cams will engage the corresponding cam follower once during each revolution of the cam cylinder, and the cam follower will be moved far enough to engage one of the movable contacts 45, 46 to move it against one of the fixed contacts 47, 48, respectively. The fixed contacts 47, 48 are connected with leads 9 and 7, respectively. The cam followers will be made of insulating material when employed, as shown, to operate movable contacts by direct engagement therewith.

Lead 8 is connected to a source of electricity, here shown as battery 49, and another lead 50 extends from battery 49 to a pair of conductors 51 each terminating in a movable conductor 52 having a contact 53 at the free end. Two resistances 54, 55, which are essentially rheostats, are connected by leads 56, 57, respectively, with the movable contacts 45, 46. These resistances are divided into segments by means of a plurality of conductors 58, each conductor 58 having a movable conductor 59 connected thereto, with a contact 60 at the free end of each movable conductor 59. An arm 62 is rigidly fixed to annular yoke 24 and therefore moves with gear 21. As the end of arm 62 engages either contact 53, movable conductor 52 is bent or rocked until it engages contact 60 of the adjacent conductor 59. Thus a circuit is completed, but with all the resistance (54 or 55, as the case may be) in series with the servomotor field. The servomotor thus starts slowly. Further movement of arm 62 cuts out some of the resistance, and the servomotor speeds up. Re-

versal of the servomotor is effected by moving arm 62 in the opposite direction, with concomitant sequential cutting out of the resistance as previously described. The described resistances are similar in principle to the Westinghouse "Silverstat," and provide a compact series of contactors by which any series of resistances may be tapped in and out of the servomotor circuit, to control rotation of the servomotor in either direction.

Operation

Assuming that the parts are in neutral position, as illustrated in the figure, there can be no change as long as there is no adjustment of shaft 17, the servomotor necessarily remaining stationary because its circuit is open. As soon as crank-wheel 15 is turned sufficiently in either direction, arm 62 effects a closing of the motor circuit and the servomotor starts slowly due to the full resistance (54 or 55) in the field circuit. Energization of the servomotor is only momentary, because of the shape of cam 32, or 33, which lifts the corresponding bell crank lever to close the circuit once during each revolution of shaft 26. With further adjustment of yoke 23, hence of either cam cylinder 30, 31, away from the neutral position, the corresponding bell crank lever will effect a longer closing of the contacts 45, 47 or 46, 48 as the case may be, and the energization of the servomotor will take place through a longer proportion of the period of one revolution of shaft 26, and in addition, the speed of the servomotor will be increased because less resistance will be in the field circuit. Any movement of the servomotor will of course be reflected in the object whose position is controlled by the servomotor through the power take-off. However, the servomotor when energized rotates gear 14, which always rotates gear 21 engaging the screw threads 20 of shaft 17. Hence with shaft 17 stationary, gear 21 travels along said shaft back towards the neutral position and will usually come to a stop exactly in that position. If there is a slight overtravel, the servomotor will be reversed and the parts will be brought to neutral position by movement in the opposite direction; however, with proper design and adjustment of the parts, overtravel and hunting will seldom occur.

The described mechanism shows proportionalizing by rate and time. If proportionalizing by rate only is desired, shaft 26, the cam cylinders, the constant speed motor and the speed governor may be omitted, and the arm 62 may merely close contacts to close the motor circuit in one direction or the other through the resistances 54 or 55. If it is desired to proportionalize only the time, the resistances 54, 55 and their contacts may be omitted. The described combination of proportionalizing, both in rate and time, will provide an absolute maximum of damping (or minimum of hunting).

The purpose of the selective speed control of motor 27 and governor 29 is to provide a rapidly adjustable means for changing the "damping" characteristics of the follow-up mechanism. This is desirable to permit tuning the follow-up characteristics as is necessary to prevent undesirable hunting to match the inertia characteristics of whatever is driven from the power take-off 11. In other words, if the object driven from the power take-off 11 has a high polar moment of inertia it will require a different follow-up speed of motor 27 than if the object had a relatively low polar moment of inertia. That is, within the limits of power furnished by the servomotor. The speed-power and acceleration characteristics of

servomotor 5 are selected to drive the driven object (not shown) from power take-off 11 so that by the time switches 46 or 47 are fully closed and thus servomotor 5 is running at maximum rate, gear 21 cannot reach end of threaded portion 20 of shaft 17. It is thus seen that the servomotor speed is proportional whether in rate or time or both, to the rate at which control crank 15 is moved.

Obviously the invention may be embodied in many forms neither described nor shown.

What is claimed is:

1. A torque amplifier comprising, in combination, a reversible servomotor; circuits for said servomotor; a shaft driven by the servomotor; a power take-off driven by said shaft; an elongated gear driven by said shaft; a second gear meshing with the elongated gear; a manually adjusted shaft for moving the second gear longitudinally of the manually adjusted shaft independently of any other mechanism; there being a screw thread connection between the second gear and the manually adjusted shaft, so that rotation of the second gear by the motor-driven elongated gear will effect adjustment of the second gear on its shaft; an arm moved by adjustment of the second gear; a yoke secured to said arm; a splined shaft; a pair of cam cylinders movable on said splined shaft; a pair of coil springs tending to hold the cam cylinders against the yoke on either side of the same, so that adjustment of the second gear may effect movement of one of the cam cylinders against the resistance of one of the coil springs; an electric motor driving the splined shaft and hence the cam cylinders at a reduced speed; operator-controlled means for varying the speed of said motor; cams on the cam cylinders; cam followers riding on the cam cylinders and adapted to be actuated by the cams; contacts engaged by said cam followers when so actuated to close said circuits governing the servomotor; the springs normally holding the cam cylinders in neutral position and the cam followers then riding on the cam cylinders with-

out contact with the cams; a pair of resistances in the servomotor circuits; conductors dividing each resistance into segments; an arm secured to said yoke and adapted to engage said conductors sequentially to progressively cut out the resistance as the arm is moved farther from the neutral position; the servomotor speeding up in either direction as the resistance is cut out; the cams being so shaped that a greater proportion of the total time of one revolution of the splined shaft is expended in holding the servomotor circuit closed, the further the arm is adjusted from the neutral position.

2. A torque amplifier comprising, in combination, a reversible electric servomotor; a power take-off actuated by the servomotor; an elongated gear directly driven by the servomotor; a second gear meshing with the elongated gear; a screw-threaded shaft with which the second gear engages by means of screw threads; an operator-controlled mechanism for turning the screw-threaded shaft thereby to adjust the position of the second gear thereon; the second gear remaining in mesh with the elongated gear whatever its adjustment; a motor circuit including contacts for governing the direction of rotation of the servomotor; an arm moved by the second gear and hence adjustable by the operator, and adapted to close the motor circuit through said contacts to effect rotation of the servomotor in one direction or the other; a pair of cams, one on either side of the arm; a shaft on which the cams are splined; a constant speed motor; mechanical connections between the constant speed motor and the splined shaft so that the cams are constantly driven at a reduced rate of speed; cam followers respectively actuated by the cams and in turn closing the respective contacts to actuate the servomotor in one direction or the other; and springs acting to center the cams on the splined shaft, said cams being so constructed that when centered the cam followers are not actuated.

HOWARD M. McCOY.
